CLOSURE

Alphons Isele, Neudorf, Switzerland

Application July 10, 1940, Serial No. 344,639½

1 Claim. (Cl. 215—40)

This invention relates to air-tight and water-tight closures for bottles and other containers of different forms and types and made of any suitable material, such as glass, sheet metal, such as aluminum, Bakelite, porcelain, and the like.

An object of the present invention is the provision of a closure for bottles, glasses and cans for fruits, preserves, meats and the like, said closure being so constructed that it remains tight at a predetermined pressure prevailing within the container.

Another object is the provision of a closure for bottles and other containers, which is capable of performing the function of a safety-valve to allow some fluid to escape from the interior of the container until the pressure within the container drops to a desired level.

Other objects of the present invention will become apparent in the course of the following specification.

The invention will appear more clearly from the following detailed description when taken in connection with the accompanying drawing showing by way of example preferred embodiments of the inventive idea.

In the drawing:

Figure 1 shows partly in side elevation and partly in section a bottle carrying a cover.

Figure 2 shows partly in section and partly in bottom view the cover illustrated in Figure 1.

Figure 3 is partly a section through and partly a side elevation of the cover shown in Figure 2.

Figure 4 is a top view of the packing ring shown in Figure 1.

Figure 5 shows the packing ring of Figure 4 partly in side elevation and partly in section.

The closure shown in Figures 1 to 5 of the drawing comprises a cover 80 which may be applied over a bottle 81. The bottle 81 has an annular projection or ring 82 serving as a support for a packing ring 83 provided with a tapered knurled surface 84. The surface 84 may be substituted by any suitable means engaging the cover. The bottle 81 is also provided with an edge or bead 85 and a helical rib 86.

The cover 80 is provided with outer ribs 87 and inner helical grooves 88 which fit over the rib 86. The interior of the cover 80 is provided with a knurled surface 89 fitting over the knurled surface 84 of the packing ring 83.

The inner top surface of the cover 80 carries an annular projection 90 serving as an abutment for a packing ring 91.

The ring 83 has a knurled surface 84 which is firmly engaged by the surface 89 of the cover

80. Due to this form of the ring 83, the cover is prevented from becoming loose in the course of transportation or while it is being shaken.

As shown in Figure 1, the annular rib 90 is smaller in diameter than the inner diameter of the opening of the bottle 81, so that when the cover 80 is screwed on, parts of the ring 91 are clamped between the rib 90 and the bead 85.

It is possible to provide the ribs 87 in such a position upon the cover 80, that the circumference of the cover will be diminished instead of increased, when the cover is screwed on.

The described constructions of the packing ring and the parts co-operating therewith, make it possible to close a container in a secure air-tight and water-tight manner merely by screwing the cover upon the container; this secures the cover firmly upon the container, so that it cannot fall off even when inner pressure forces are developed

15 within the container or when the container is shaken in the course of transportation. However, the cover may be conveniently removed or attached by hand, even when the pressure within the container is quite great.

20 Since the packing ring is permanently connected with the cover or the container, it cannot be lost and is cleaned easily. However, any defective packing ring may be conveniently removed by hand and replaced by a new one.

25 A further advantage of the described constructions is that the container and its cover may be used any number of times without any danger of breakage or injury.

30 It is not necessary that special types of bottles or containers be manufactured for use with the described closures, since packing rings of the described type can be applied over beads or depressions provided in the necks of existing bottles or containers.

35 The packing rings prevent the formation of drops upon the edges of containers, so that after a liquid is poured out of the container no further drops can be formed.

40 Another advantage of the packing rings is that they protect the neck and edges of the bottles or containers from cracking, breakage or other damage.

45 It should be noted that the exact dimensions of the covers for the containers can be determined only after the placement of the packing rings upon the containers since only then it is possible to determine the extent of shrinkage or contraction of the container resulting from the strain upon the material of the packing rings, which is admissible up to 10%.

Bottles provided with closing means of the described type are particularly suitable for the manufacture of sparkling wine or sparkling hock, since in the manufacture of these wines it is necessary to shake the bottles many times. It is easy to close and open the described covers in the course of this manufacture.

Since the bottom of the cover presses against the edge of the container when the latter is closed, drops of liquid cannot escape out of the container.

The packing rings shown in the illustrated constructions may be provided with the usual locking devices which prevent the rings from turning. However, whenever these devices cannot be used, the firm mounting of a ring may be assured by a suitable selection of the amount of elasticity of the ring or the material of which it is made. Namely, the elasticity should be so selected that the pressure per unit of area, created by the stress upon the material of the ring, should be greater than the force which is necessary to affix the cover firmly and permanently upon the container or to remove the cover from the container; however, to avoid a destruction of the elastic ring, the pressure to which it is subjected should not exceed one tenth of its elasticity limit. Furthermore, the elasticity of the ring should be such that not only the ring is prevented from turning, but that jamming or clamping of the ring is avoided as well.

Through the use of the packing rings, it is

possible to overcome securely and without fail any differences in size which occur in the manufacture of different bottles and containers made of different materials.

5 When gas pressure within a container becomes too great, the cover may be unscrewed or slightly opened to allow the gases to escape and thereby diminish the pressure, without any danger that the cover will fly out in the air.

10 It is apparent that the specific illustrations shown above have been given by way of illustration and not by way of limitation, and that the structures above described are subject to wide variation and modification without departing from the scope or intent of the present invention, all of which variations and modifications are to be included within the scope of the present invention.

What is claimed is:

20 In combination, a container member having an edge portion which encloses an opening and which comprises at least one helical rib and an annular projection situated below said rib, a closure member for closing said opening, said closure member having a skirt which comprises an inner helical groove meshing with said helical rib, and an elastic packing ring firmly mounted upon said container member and engaging said annular projection, said packing ring having a tapered knurled surface engaging an inner knurled surface of said closure member.
